RAY H. MANSON, OF ELYRIA, OHIO, ASSIGNOR TO THE GARFORD MANUFACTURING COMPANY, OF ELYRIA, OHIO, A CORPORATION OF OHIO.

AUTOMOBILE OR MOTOR-CYCLE HORN.

1,211,208.

Specification of Letters Patent.

Patented Jan. 2, 1917.

Application filed May 15, 1915. Serial No. 28,259.

To all whom it may concern:

Be it known that I, RAY H. MANSON, a citizen of the United States, residing at Elyria, in the county of Lorain and State of Ohio, have invented certain new and useful Improvements in Automobile or Motor-Cycle Horns; and I do hereby declare the following to be a full, clear, and exact description of the invention, such as will enable others skilled in the art to which it appertains to make and use the same.

My invention relates to automobile or motor cycle horns, and more particularly to such horns in which an electric or other suitable motor is employed to cause the actuation of the diaphragm, preferably through the rotation of a roughened wheel. As is well known, horns of this type are already in general use, so that the object of my invention is to improve upon this type of horn.

In modern practice automobile horns are employed frequently under the hood of an automobile in association with the power plant of the automobile, and it is highly desirable that the horn should occupy but little space, especially in a longitudinal direction, the idea being to provide a horn which will not interfere with the access to the other machinery. The advantages of such an arrangement will be appreciated, especially in connection with six and eight cylinder engines. Horns of this type have also come to be used upon motor cycles, where the handle bars and other portions of the frame of the motor cycle are already crowded with machinery and accessories. It is very desirable that the horn employed should be small and that it should not extend far to the rear of the handle bars.

Another feature of my invention is the provision of an electric motor upon which the field coil can be wound directly in a winding machine. This greatly expedites and cheapens the manufacture of the horn, because in the past, so far as I am aware, it has been necessary to wind the field coil independently of the pole piece, then mount it on the pole piece.

One of the objects of my invention is to provide a condensed horn, and especially a "flat" horn, and at the same time to preserve the efficiency of the horn, producing such a device which is capable of making a loud signal.

Another object of my invention is to provide suitable adjusting means for horns of the type which I have mentioned.

In the operation of devices of the character to which my invention relates, the operating parts are frequently actuated at high speeds, striking hard and frequent blows, so that anything about the instrument not tightly secured will be jarred loose. For these reasons, it is difficult, if not impossible, to employ with success the adjusting means employed upon other types of horns. In my invention I employ adjusting mechanism so located, constructed and arranged that the effect of such jars and blows will be greatly reduced and in most instances entirely eliminated.

I also aim to provide suitable and convenient locking means to hold the adjusting mechanism in position after the horn is once adjusted.

Other objects of my invention and the invention itself will probably be better understood from a description of an embodiment of the invention.

Figure 1 is a side elevation of an embodiment of my invention with the rear casing cut away, to show the interior mechanism of the horn. Fig. 2 is a section on the line 2—2 of Fig. 3. Fig. 3 is a rear elevation of the horn with the casing removed. Fig. 4 is a section taken through the pole piece along the line 4—4 of Fig. 1.

Referring now to the drawing and to the embodiment of the invention illustrated therein, at 4 is shown a frame piece or supporting member, which is here illustrated as a ring of metal having a large opening 5 in the central portion thereof. The sound producing device, here shown as a sonorous diaphragm 6, is supported from this frame piece. In the form shown this is connected to the front of the frame piece by any suitable means, such as screws or bolts 7, 7' and 7''. A casing front 8 is provided which is used in front of the diaphragm and which is also connected to the member 4 by the members 7, 7' and 7''. The casing front is provided with an opening 9 for the egress of sound waves and a resonator 10 may be mounted in this opening to direct and accentuate the sound waves. A bracket 11 may also be used to connect the horn to the vehicle.

In the embodiment shown, the motor is 110

illustrated as an electric motor, which is shown at 12. The field of the motor is shown at 13 and consists preferably of a casing of soft iron. The field is provided with a plurality of wings 14, 15 and 16, by which it is connected to the member 4 by the use of screws or other suitable connecting means. I may employ the screws 7' and 7" to perform the function of connecting the motor to the member 4, in addition to connecting the diaphragm and casing front to the member 4. The armature of the motor is shown at 18. The field yoke is shown at 19 and consists of a limb 20, which is parallel to the armature, and a limb 21, which is at an angle to the armature and which is provided at its free end with an arm 22 upon which a field winding 23 is mounted. A collar 22' is shown upon the arm 22 integral therewith. The winding 23 is placed upon the arm between the collar 22' and the shoulder 22" upon the arm. This winding may be placed upon the arm 22 by an automatic winding machine prior to the placing of the armature in the yoke. The coupling link 24 of the yoke is integral with the limbs and both the limbs, the coupling link and the arm 22 are substantially parallel to the diaphragm, making the device very compact and flat. The coupling link 24 is provided with an opening 26 in which there is formed a bearing for one end 27 of the armature shaft. A removable link 30, preferably of brass is connected across the open end of the yoke 19, and is provided with an opening 31 to form a bearing for the other end of the armature shaft.

The commutator is shown at 32 and the roughened wheel at 33. An anvil 34 is mounted on the diaphragm, which is struck by the roughened wheel when the armature is rotated, causing the actuation of the diaphragm and the production of the signal. Brushes 35 are mounted in openings in the limbs 20 and 21. Suitable means, such as screws 40 are provided for connecting the link 30 to the yoke. An opening 41 is provided in the wing 14 and a threaded bushing 42 is screwed into the opening 41, which is interiorly threaded. One end 43 of the bushing bears against the back side of the member 4 at 60. The other end of the bushing is preferably provided with a head 45. The bolt 7' extends through the bore in the bushing, and a nut 46 is placed on the end of the said bolt.

When it is desired to adjust the horn, that is, to adjust the wheel 33 with respect to the anvil 34, the nut 46 is loosened and the bushing is rotated, turning against the bearing 60 and raising or lowering one end of the motor through the wing 14. The fastening means 7' and 7" have sufficient play and resiliency to permit movement

enough to properly adjust the horn, and when the horn has been adjusted, the nut 46 is screwed down, locking the bushing in position, so that it cannot rotate. It will readily be appreciated that this adjustment cannot be disturbed, no matter how hard the action of the roughened wheel upon the anvil and diaphragm, or however the horn is shaken, owing to the rotation of the motor armature, not only because the adjusting mechanism has been locked, but because it is so positioned that little or no effect of such agitations will reach the adjusting mechanism.

A rear casing 50 is employed, preferably fitting within the front casing, whose edge is turned over at 51. The casing is fastened on by some suitable means, such as by screws 52 which may be driven into openings in the yoke. Binding posts are also provided, one of which is shown at 53. Conductors lead from these binding posts to the brushes, and from the binding posts to the source of current and the circuit controller which are employed, and which are old and well understood.

I have illustrated this embodiment of my invention and the details thereof for the purpose of describing the same. It will be appreciated that departures may be made both from the form and details of the embodiment thus illustrated and described, without departing from the spirit of the invention, the invention being set forth in the appended claims.

I claim:—

1. In an automobile horn, the combination of a frame piece, a sonorous diaphragm, means to connect the diaphragm to the frame piece, an electric motor for operating the diaphragm, a field yoke for said motor, a plurality of wings on said yoke, means to connect the motor through said wings to the frame piece, an armature for the motor mounted in the yoke, a limb on the yoke parallel to the diaphragm and to the armature shaft, a second limb on the yoke parallel to the diaphragm but inclined to the armature shaft, an arm on said second named limb, a field winding on said arm, a link integral with said limbs and connecting the same together at one end, a bearing in said link for the armature shaft, a second link for connecting the other ends of the limbs, said second link being removable from said limbs, a bearing in said link for the other end of the armature shaft, said limbs being provided with openings, brushes in said openings, an anvil on the diaphragm and a roughened wheel rotated by the motor for striking the anvil and causing the actuation of the diaphragm.

2. In an automobile or motor cycle horn, the combination of a flat frame piece provided with an opening in the central portion

- thereof, a sonorous diaphragm, means to connect the diaphragm to the front of the frame piece, said diaphragm extending over the opening in the frame piece, a field yoke for an electric motor, comprising a plurality of limbs and an interconnecting link, a plurality of wings integral with said yoke, means to connect said wings to the back of the frame piece, an armature mounted in said yoke, said interconnecting link being provided with an opening forming a bearing for one end of the armature shaft, a removable, interconnecting link connecting the free ends of the limbs of the yoke, an opening in said removable link forming a bearing for the other end of the armature shaft, one of the limbs of the yoke being parallel to the armature shaft and the other inclined to the armature shaft, an arm on the free end of the inclined limb extending toward the armature, a field coil on said limb, said limbs being provided with openings for the commutator brushes, brushes in said openings, an anvil on the diaphragm and a roughened wheel operated by the armature for vibrating the diaphragm through the anvil.
3. In an automobile or motor cycle horn, the combination of a frame piece, a diaphragm connected therewith, a field yoke consisting of a pair of limbs and an interconnecting link, means to connect the yoke to the frame piece, said limbs and link being parallel to the diaphragm, an armature in said yoke, one of the limbs of the yoke being parallel to the armature shaft, the other limb being inclined to the armature shaft, an arm on the free end of the inclined limb of the yoke, a field coil on said arm and means operated by the motor for vibrating the diaphragm.
4. In an automobile horn, the combination of a frame piece, a diaphragm connected thereto, a field yoke consisting of a pair of limbs and an interconnecting link integral therewith, a removable link for connecting together the free ends of the limbs, means to connect the yoke to the frame piece, said links being provided with bearings for an armature shaft, an armature in said yoke having the ends of its shaft in said bearings, the limbs of the yoke, the interconnecting links and the armature being parallel to the diaphragm, one of said limbs being inclined to the armature shaft, an arm on said limb, a field coil on said arm and means including a roughened wheel controlled by the armature for causing the vibration of the diaphragm.
5. In an automobile horn, the combination of a frame piece, a diaphragm, means for operating the diaphragm including an electric motor comprising an armature parallel to the diaphragm, a field yoke provided with limbs parallel to the diaphragm, one of the limbs being inclined to the shaft of the armature, an arm on said limb, a field coil on said arm and means to connect the motor to the frame piece and mechanism including a roughened wheel by means of which the armature causes the actuation of the diaphragm when rotated.
6. In an automobile horn, the combination of a frame piece, a diaphragm connected to one side thereof, an electric motor connected to the other side of the frame piece, an armature for said motor parallel to the diaphragm, a yoke for the motor, wings on the yoke integral therewith, means to connect the motor through said wings to the frame piece, the limbs of the yoke being parallel to the diaphragm, one of said limbs being inclined to the motor shaft, an arm on the free end of said inclined limb, a field coil on said arm and means including a roughened wheel for causing the actuation of the diaphragm when the armature is rotated.
7. In an automobile horn, the combination of a flat frame piece provided with an opening in the central portion thereof, a diaphragm connected to the frame piece, an electric motor provided with an armature parallel to the diaphragm, a yoke for the motor consisting of two limbs and an integral interconnecting link, a second link connecting the free ends of the limbs and removable therefrom, bearings in said links for the armature shaft, one of the limbs being inclined to the armature shaft, an arm on said inclined limb, said limbs, said arm and said interconnecting links being parallel to the diaphragm, a field coil on said arm, means for connecting the motor to the frame piece and mechanism including a roughened wheel through which the motor actuates the diaphragm.
8. In an automobile horn, the combination of a frame piece, a diaphragm connected to the frame piece, an electric motor comprising an armature and a field yoke, said yoke consisting of two limbs and an interconnecting link, a wing on each limb and a wing on the link, means to connect said motor through said wings to the frame piece, the second link connecting the free ends of the limbs of the yoke, said second link being removable from said yoke, bearings in said links for the armature shaft, a field coil on one of said limbs and means including a roughened wheel through which the motor actuates the diaphragm.
9. In an automobile horn, the combination of a frame piece, a diaphragm, means for operating the diaphragm, means for adjusting the operating means with respect to the frame piece including a hollow bushing threaded into a portion of the operating means and bearing against the frame piece, means for connecting the diaphragm to the frame piece

- and operating means together including a bolt extending through the hollow bushing and a nut on said bolt.
10. In an automobile horn, the combination of a frame piece member, a diaphragm, means for operating the diaphragm, means for adjusting the operating means with respect to the diaphragm including a hollow threaded bushing and means for locking 10 said parts in adjusted position consisting of a bolt extending through the hole in the bushing and a nut on the bolt.
11. In an automobile horn, the combination of a diaphragm, an electric motor, 15 means to connect the motor and diaphragm together with the motor parallel to the diaphragm, said means being applied to the motor at three points and means at one of said points to tilt the motor about the axis 20 including the other two points.
12. In an automobile horn, the combination of a frame piece, a diaphragm, a motor for operating the diaphragm, three connecting means for connecting the motor to 25 the frame piece, and apparatus at one of said connecting means for tilting the motor about an axis through the other two connecting means to adjust the motor with respect to the diaphragm.
- 30 13. In an automobile horn, the combination of a flat frame piece having its central portion cut away to form an opening therein, a sonorous diaphragm mounted on the front of the frame piece and extending over 35 the opening, means to connect the diaphragm to the front of the frame piece, an electric motor connected to the back of the frame piece, including a field yoke, an armature and a commutator, a plurality of wings 40 on said yoke through which the motor is connected to the back of the frame piece, said yoke comprising two limbs and an integral interconnecting link, each limb and the link being connected to one of said wings, 45 a second link removably connected to the free ends of the limbs, each link being provided with an opening, a bearing in each opening for an end of the armature shaft, each limb provided with an opening, brushes 50 mounted in said openings, the armature, said links and said limbs being parallel to the diaphragm, one of said limbs being parallel to the armature shaft, the other of said limbs being inclined to the 55 armature shaft, an arm on the free end of the inclined limb parallel to the diaphragm and substantially perpendicular to the armature shaft, a field winding on said arm, an anvil on the diaphragm and a roughened 60 wheel adapted to intermittently engage said anvil when the armature is rotated, said wheel being on the armature shaft between the armature coil and the commutator, said
- anvil extending through the opening in the frame piece.
14. In an automobile horn, the combination of a frame member, a vibratile diaphragm connected to the frame member, an electric motor connected to the frame member having operative connection with the diaphragm, said motor comprising a yoke having two limbs parallel to the diaphragm, an arm on one of said limbs, a collar integral with said arm, a shoulder formed on said limb, and a winding between said shoulder and said collar.
15. In an automobile horn, the combination of a flat frame piece having its central portion cut away to form an opening therein, a sonorous diaphragm mounted on the front of the frame piece and extending over the opening, means to connect the diaphragm to the front of the frame piece, an electric motor connected to the back of the frame piece including a field yoke, an armature and a commutator, means to connect the motor to the frame piece, said field yoke comprising two limbs and an integral interconnecting link, a second link removably connected to the free ends of the limbs, each link being provided with an opening, a bearing in each opening for an end of the armature shaft, each limb provided with an opening, brushes mounted in said openings, the armature, said links and said limbs being parallel to the diaphragm, one of said limbs being inclined to the armature shaft, an arm on the free end of the inclined limb parallel to the diaphragm and substantially perpendicular to the armature shaft, a collar on said arm integral therewith, a shoulder on said arm, a field winding on said arm between the collar and the shoulder, an anvil on the diaphragm and a roughened wheel adapted to intermittently engage said anvil when the armature is rotated.
16. In an automobile horn, the combination of a flat frame piece, a diaphragm connected to the frame piece, an electric motor connected to the frame piece, said motor consisting of a yoke provided with two limbs and an integral interconnecting link, an armature shaft between the limbs, one of the limbs being inclined to the armature shaft, an arm on the free end of said limb having a shoulder thereon, a collar on said arm integral therewith, a field winding between the collar and the shoulder, means to connect the motor to the frame piece with said limbs, said armature, said interconnecting link and said arm parallel to the diaphragm and apparatus through which the armature actuates the diaphragm.

I have signed my name hereto this 10th day of May, 1915.

RAY H. MANSON.
